SHAPING METHOD AND APPARATUS

James L. Adams, Jr., Youngstown, Ohio, assignor
to The Youngstown Sheet and Tube Company,
Youngstown, Ohio, a corporation of Ohio

Application December 17, 1931, Serial No. 581,633

10 Claims. (Cl. 51—251)

The present invention relates broadly to the art of metal working, and more particularly to the phase thereof concerned with metal tube rolling, although the utility of the invention is applicable to any branch of the metal working art including a circular or a contour pass through which material travels, and more especially a roll pass composed of a plurality of rolls having peripheral portions so disposed as to define the 5 contour of such a pass. Such roll passes may comprise any desired number of rolls, although from two or three to five or more rolls are customarily utilized. The utility of the invention, however, is not limited in this respect.

It has heretofore been customary in the art both in forming a roll pass initially, and in resurfacing the pass, to individually shape and finish the rolls, the machinist bringing them as 15 nearly as he could to what was thought to be the proper shape. The bearings were also accurately machined and fitted in an attempt to get as nearly the desired contour in the pass as possible with all of the parts assembled. Even though these operations were carried out by the most skillful and 20 accurate workmen normally available, deviations in contour from the desired shape were often present, it being practically impossible to separately machine all of the parts and then put them together in such manner as to form a perfectly 25 shaped pass. This is especially true where the pass consists of from three to five or more rolls.

The present invention has for one of its objects the production of a precision pass which, for all practical purposes, is a true circle or other pre- 30 determined shape, and also the production and maintenance of such a pass more easily, quickly, and at less expense, both as to time and labor, than has been possible with the methods heretofore used.

Another object of the invention is to effect a 35 surfacing of the rolls after the same have all been assembled together, thereby not only facilitating and speeding up the roll finishing operation, but insuring a more nearly truly contoured 40 circular or other determined pass.

The invention is applicable not only to the initial formation of the pass, but to the maintenance of the desired contour therein by finally 45 finishing the rolls or other pass forming means in place, from time to time as wear and use may require.

My invention can be carried out by suitably moving a cutting tool very slowly around the 50 pass contour while at the same time rotating the rolls slowly under their own power, but in the ac-

companying drawings there is shown by way of illustration only, a preferred embodiment of the present invention, as arranged for circular contour grinding only. In the drawings:

Figure 1 is a vertical sectional view, with certain of the parts in elevation, showing one form of pass grinding means in accordance with the present invention;

Figure 2 is a view partly in end elevation, and partly in section along the line II—II of Figure 1, 10 looking in the direction of the arrows;

Figure 3 is a view similar to Figure 2, but on an enlarged scale for the purpose of showing certain details of construction; and

Figure 4 is a longitudinal sectional view through 15 a portion of the roll grinding mechanism, the view being taken along the line IV—IV of Figure 3, looking in the direction of the arrows and with certain of the parts rotated to a different position than that of Figure 3.

In the drawings the invention is illustrated as applied for use in connection with a roll pass constituting part of a welding machine, or a pipe straightening machine. While such an illustration serves for purposes of a clearer understanding of the invention, it is to be understood that the invention is not limited in this respect, it being equally applicable to any substantially circular pass, or to any other determined contour readily attainable, as before pointed out.

Before entering into a detailed description of the drawings, it may be pointed out that in order to grind a substantially truly circular pass, there are certain requirements which must be satisfactorily met. In the first place, the grinder itself must be rotatable about its own axis. Secondly, the diameter of the grinding element should be less than the desired diameter of the finished pass so that the element has a limited zone of action 35 at all times. Thirdly, the entire element in addition to rotating, must be caused to have a planetary motion so as to cause the grinding portion thereof to successively contact progressive points peripherally of the pass. Lastly, the mountings and feed adjustments must be such as to permit 40 such movements to be easily and accurately obtained, and readily maintained in spite of normal cutter wear, while the entire device is supported in cooperative relation to the pass. Furthermore, in the case of a roll pass, the rolls themselves will 45 preferably be very slowly and continuously rotated around their own axes during the surfacing operation, so that the entire peripheries thereof will be subjected progressively to the desired shaping or finishing and smoothing action.

Referring more particularly to Figures 1 and 2 of the drawings, there is shown a frame 2 in which is mounted a series of rolls 3 defining the pass which is to be ground in accordance with the present invention. Cooperating with the roll frame is a grinder frame herein illustrated as comprising a series of arms 4 adapted to be secured to the frame 2 so as to support the grinder in the desired concentric or operative relation to the rolls and pass axis. The grinder frame includes a horizontally projecting bracket 5 in which is carried a king pin 6 forming a rotatable mounting for a U-shaped motor bracket 7, and permitting the motor bracket to swing about a substantially vertical axis A—A including the axis of the king pin, and hereinafter referred to as the grinding motor axis.

Between the arms of the U-bracket 7 is journaled a grinding motor 8 on trunnions 9, the trunnions forming a second pivotal or swinging mounting along the axis B—B, Figure 2, for the grinding motor 8 effective in a direction substantially normal to the axis A—A, and forming in effect a universal mounting for the grinding motor, permitting it to be adjusted in any direction at will about a plurality of substantially normally extending, mutually intersecting axes.

The armature of the motor drives a grinder shaft 10 on which is located a grinding element 11 illustrated as having its edges relieved to provide a limited grinding zone C at the periphery of the element. When the motor 8 is operated, the grinding element may be caused to rotate about its own axis in contact with a limited portion of one of the rolls 3. If the parts were continuously retained in this position, one of the rolls 3 would be unevenly ground at the expense of the other rolls. To obviate this action and insure uniformity of grinding, it is necessary to bodily rotate the grinding element in an orbit around an axis D—D extending through the point of intersection of the axes A—A and B—B, and intersecting the desired true center of the finished pass.

This movement is obtained by providing within the grinder frame a rotatable bushing 12. The bushing 12, as illustrated more particularly in Figure 3 of the drawings, is adapted to be continuously and slowly rotated about the axis D—D by means of a motor 14, hereinafter described as the orbital motor. The orbital motor drives a worm 15 meshing with a worm wheel 16 keyed to a shaft 17. This shaft, which is mounted in suitable bearings in the grinder frame, carries a worm 18 continuously in mesh with teeth 19 formed in the periphery of the bushing 12, so that upon operation of the orbital motor 14, the bushing 12 is continuously rotated.

Cooperating with the bushing 12 is a fixed bushing 20, the bushings 12 and 20 having their inner surfaces machined to form a bearing for a ball shaped bushing 21 having an opening eccentrically formed therein with respect to its periphery. Journaled in this opening is a second eccentric bushing 22. In accordance with the preferred method of construction, the eccentricity of the ball shaped bushing 21 is exactly equal to the eccentricity of the bushing 22, whereby with the two parts in proper relationship, i. e., offset 180° one with respect to the other, they will provide an opening concentric to the axis of the ball shaped bushing 21. By relatively adjusting these parts, however, the amount of eccentricity of the opening may be varied at will. In this opening there is carried an anti-friction bearing 23 for the grinder shaft 10. Relative adjustment of the

bushings 21 and 22 enables the grinder shaft to be adjusted radially by any desired amount at the will of the operator.

This relative adjustment is obtained by providing the eccentric 22 with teeth 24 around its periphery, which teeth are engaged by a worm 25 on a shaft 26 carrying at its outer end a star wheel 27. The star wheel may be either periodically rotated by hand, or may be automatically rotated during the operation of the grinder by a finger 28 carried by the grinder frame.

For insuring the desired planetary or orbital movement of the grinder when the bushing 12 is rotated, this bushing and the ball shaped bushing 21 are keyed together by a ball key 29 working in an elongated slot 30 in the periphery of the bushing 21. This construction insures concomitant rotation of the parts, but permits the grinder shaft to swing about both the axis A—A and the axis B—B during its operation. Thus, the grinding zone C is caused to progressively travel around the inner surface of the pass, and contact successive peripheral portions thereof in such manner that the entire pass defining surface of the rolls 3 is subjected to a uniform grinding action.

To insure grinding the entire periphery of each of the rolls 3 uniformly, they are in turn caused to very slowly rotate about their own axes, and the operation is continued until the desired configuration of the pass is obtained.

The grinder is illustrated as being substantially encased between dust shields 31 and 32, located on opposite sides of the wheel 11, and provided with felts or other suitable wipers 33 continuously in engagement with the roll peripheries; but this is not an essential element. All anti-friction bearings are of course similarly protected by small felt dust shield rings, or wipers.

By mounting the grinder on anti-friction bearings of the character herein illustrated, rotation of the grinder is facilitated. By relieving the edges of the grinding wheel, thus narrowing down the width of the wheel in contact with the work, the tendency otherwise present to clog up or "load" the grinding surface, is in considerable part overcome.

In accordance with the present invention, it is not necessary to finish grind the rolls which are to form the roll pass, prior to inserting them in a mill. As an actual matter of fact, it is preferable to take the turned, but unground rolls, and then rotate them about their own axes in position in the roll stand while the grinder is in operation, continuing the grinding until the rolls are of the proper contour. By this means, a practically perfect pass can be initially obtained prior to the commencement of operation of the mill, or it can be maintained thereafter by regrinding during the use of the mill without dismantling the roll pass, and in considerably less time and at a much less expense than has heretofore been possible.

In practicing the invention in connection with rolls of hard steel, I have found that desirable results are accomplished by utilizing a relatively soft grade of grinding wheel, of silicon carbide type with bakelite binder, and soaking the wheel well with ordinary machine oil before it is used. It will be understood, however, that this is not an essential part of the present invention, the invention contemplating the use of any type of surface element or tool most suitable to the purposes.

From the foregoing description taken in connection with the accompanying drawings, it will be apparent to those skilled in the art that my invention

vention provides a method and apparatus which satisfactorily answers the requirements for forming and maintaining a proper circular or other readily derivable pass. The different characteristic movements of the grinder, including rotation about its own axis, orbital movement about the axis of the roll pass, together with accurate adjustment of the parts, can all be obtained at a minimum cost and in a minimum of time, and 10 with correspondingly greater accuracy in the contour obtained, than by the use of the customary means previously utilized.

While I have herein illustrated and described certain preferred features of the invention, it will be understood that changes in the construction and operation disclosed herein, as well as in the position and operation of the parts and their details of construction, may be made without departing either from the spirit of the present invention or the scope of my broader claims. For example, by making use of an additional eccentric sleeve mounted between the present inner one and the shaft, and utilizing a somewhat smaller grinding wheel diameter, and appropriate driving gearing for such added eccentric, it becomes possible to grind an elliptical pass, or one similar to a square with well rounded corners, or a similarly rounded triangle, etc. But as my claims specifically refer to illustrated constructions, these obvious modifications are not shown on the drawings, being here cited simply to show the possibilities of the process. A lathe tool might be utilized instead of a rotating grinder, and carried slowly around the pass orbit, with the rolls in rotation against it. In this construction all high speed axial rotation is dispensed with, but the same accuracy of result is accomplished to a measurable degree, at least.

I claim:

40 1. In a grinding apparatus, a grinder frame, a motor supported by said frame for movement about a plurality of substantially normal mutually intersecting axes, a motor shaft, a grinding element carried by said shaft, a support for said shaft including a plurality of eccentrics, means for adjusting one of said eccentrics relatively to the other, and means for rotating said support.

2. In a grinding apparatus, a grinder frame, a motor supported by said frame for movement about a plurality of substantially normal mutually intersecting axes, a motor shaft, a grinding element carried by said shaft, a support for said shaft including a plurality of eccentrics, means for adjusting one of said eccentrics relatively to the other, and means for rotating said support, said last mentioned means including a second motor carried by said frame.

50 3. In an apparatus for accurately surfacing a rotating, assembled, single-plane roll pass, a surfacing tool progressively movable slowly transverse to the general roll surface motion, an eccentric carrying said tool, a surrounding eccentric mounting the first eccentric and very slowly rotatable automatically and relative thereto so as to provide a slow, radial feed for said tool, and means for continuously and slowly rotating both eccentrics together as one unit to carry said surfacing tool repeatedly around the desired pass contour and in substantially the plane of said pass.

60 4. In an apparatus for re-surfacing the rolls of a roll stand, a tool-frame secured thereto, a cutting element supported by said frame, a motor for

rapidly rotating said element transverse to the motion of said rolls, a universal mounting for said motor, and means for repeatedly moving said motor slowly about said universal mounting during rotation of said element, said means including an automatically adjusted eccentric mounting for said element to feed the latter, and means for slowly and repeatedly rotating said eccentric mounting.

5. In an apparatus for accurately surfacing an assembled roll pass to a predetermined contour, a surfacing tool mounted on a shaft, and means including an eccentric mounted for universal movement for slowly carrying said tool progressively around the desired contour of said roll pass 15 in substantially the plane of the latter.

6. In an apparatus for accurately surfacing an assembled roll pass to a predetermined contour, a surfacing tool mounted on a shaft, means for carrying the working face of said tool progressively around the desired contour of said roll pass including a bearing for said shaft supported in an eccentric mounted for universal movement, and means for adjusting the final mean diameter of the finished pass.

7. In an apparatus for accurately surfacing an assembled circular roll pass, a surfacing tool mounted on a shaft, means for carrying the working face of said tool progressively around the central axis of said roll pass and substantially 30 in the plane of the latter, including a universally mounted eccentric supporting a bearing for the shaft, and a universally mounted motor direct-connected to the shaft.

8. In an apparatus for accurately surfacing an assembled roll pass to a predetermined contour, a surfacing tool mounted on a shaft, means for carrying said tool progressively around the contour of said roll pass, a motor direct-connected 35 to the shaft, and means pivotally supporting the motor for universal movement, whereby said surfacing tool engages the working faces of the rolls forming said pass.

9. An apparatus for surfacing a moving roll pass including a roll stand arranged to mount 45 and drive pass-forming rolls journaled therein, comprising a surfacing machine frame mounted on said roll stand, a power-driven shaft mounted upon said frame and having a surfacing member 50 thereon substantially within the plane of said roll pass, automatic means carrying said surfacing member through a predetermined orbit around said roll pass and in contact with said rolls, said means including an eccentric universally mounted and having a bearing for said shaft, and feeding means for said surfacing member operable 55 to increase the cut on the moving rolls.

10. An apparatus for surfacing a roll pass including a roll stand frame adapted to support 60 and drive pass-forming rolls mounted rotatably therein, comprising a tool support secured to said frame, a bearing pivoted on the support for universal movement, a shaft journaled therein, a cutting element carried on the shaft and adapted to engage said rolls substantially in the plane of 65 said roll pass, means operatively actuating said cutting element while so supported, and associated means causing said cutting element to travel in a predetermined orbital path about a 70 point on the axis of the element but spaced laterally thereof, during the rotation of the driven rolls and transverse of the surface movement thereof.
